UNITED STATES PATENT OFFICE

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING-MACHINE.

1,393,177.

Specification of Letters Patent. Patented Oct. 11, 1921.

Application filed December 28, 1917. Serial No. 209,247.

To all whom it may concern:

Be it known that I, JESSE A. B. SMITH, a citizen of the United States, residing in Stamford, in the county of Fairfield and 5 State of Connecticut, have invented certain new and useful Improvements in Typewriting-Machines, of which the following is a specification.

This invention relates to machines of the 10 class shown in the patent to Wernery and Smith, No. 1,132,055, dated March 16, 1915, in which the web which is longitudinally folded is fed around the revoluble platen of a typewriting machine, with carbon sheets 15 placed between the plies of the web, these carbon sheets being shiftable backwardly to cooperate with fresh portions of the web from time to time as required, and the platen being displaceable to permit the webs 20 to be straightened out sufficiently to allow for this backward shifting of the carbons.

One feature of the present invention relates to a provision whereby carbons may be carried between the plies of a web whose 25 folds are all along one side, one fold within another instead of being upon alternate sides, as in said Wernery and Smith patent. In order to accomplish this, I provide for holding the carbon sheets a set of arms or 30 blades which are all attached to a support on one side of the carbon carrier and all projecting toward the opposite side of the latter from said support, so as to enable the carbons to enter between all the plies in the 35 web.

In order to overcome the difficulty presented by seeking to mount so many blades at one side of the machine, I employ, in connection with the usual number of mounts 40 or steps, a larger number of blades, placing two or more blades upon each of said mounts or steps. Moreover, I provide for each mount or step two bearings or securing means, one for each blade, so that one of the 45 blades may be omitted from one or more of the steps or mounts if the blades are not all needed for the particular work in hand. It will be understood that this forms a very compact arrangement, which is a desideratum because it reduces the extent of unused 50

carbon at the heads of the sheets; the extent of such unused portion depending upon the distance to which the blades are strung along the machine from front to rear, and a spreading arrangement of the blades being avoided by the expedient of doubling up, as described. Moreover, the doubling up of the blades avoids the necessity of extending the run or range of action of the carbon carrier which would be required if 55 the blades were placed one behind another. Provision is further made for permitting the resetting of some of the blades when required for use with fan-fold webs, as in said Wernery and Smith patent. 60

Other features and advantages will hereinafter appear. 65

In the accompanying drawings,

Figure 1 is a perspective view of an Underwood front-strike typewriting machine 70 of the class set forth in said Wernery and Smith patent, showing the same adapted for a nest of folded plies of web.

Fig. 2 is a cross-sectional front elevation, showing diagrammatically the relationship 75 of the nest of folds and the carbon-carrying blades.

Fig. 3 is a similar elevation, showing the parts rearranged for a fan-fold web.

Fig. 4 is a perspective view of parts 80 slightly separated to show their structure.

Fig. 5 shows diagrammatically how a carbon is folded back over one of the left-hand blades of Fig. 3.

There is led into the machine a web 10, 85 comprising a set of folded plies 11, each folded along the middle and one fold tucked into another. The carbons 12 are interleaved between the plies 11 and carried upon the blades 13, which all extend inwardly 90 from one side of the carbon carrier or slide 14, which, by means of a handle, not shown, is used for drawing back all of the carbons to underlie fresh portions of the web as soon as one portion has been typed, as in said 95 patent. Upon one side of this carbon carrier are provided steps 15, which serve as mounts for said blades. Certain of said blades are mounted directly upon the steps by means of dowel pins or studs 16, which 100

project down from the hubs of the blades into holes 17 forming sockets in the steps, each blade having a clip 18 for holding the carbon 12 thereon. The clip 18 is pivoted 5 on a headed stud 18^a, forming a finger-piece.

Each blade 13 in the set may be surmounted 10 by another blade 19, which may have dowels 20 to press down into other holes 21, forming sockets in said steps; said dowels 20 also passing through holes 22, that are formed in the first-mentioned blades 13 and the clips 18 whereby the clips 18 are locked in closed position. The steps are broadened 15 to give room for the two sets of blades 13, 19 in each case, and, if desired, the broadened steps may be formed by placing together side by side two single sets of steps 15, 15^a, as illustrated in Figs. 2 and 20 4. The surmounting or overlying blades 19 thus rest upon and are anchored to the lower blades 13, but, nevertheless, are secured to the steps 15^a by means of the pins 20. The upper blades 19 are raised above 25 the lower blades 13 by means of distance blocks or spacers 19^a provided on the lower sides of the pin-carrying ends of the upper blades 19, as shown in Figs. 1 to 4, inclusive. The free ends of the blades 13 and 19 are in 30 substantial alinement, but the upper blades 19 are shorter than the lower blades 13 and have their pin-carrying ends displaced inwardly sufficiently to avoid interference with the finger-pieces 18^a of the lower 35 blades 13.

Thus, it will be seen that a large number of blades can be compactly fitted in a very small space with the benefit of economizing all the carbon sheets, and the further benefit 40 of making it unnecessary to lengthen the throw of the carbon carrier which would be the case if all of the blades which project the same way were arranged one behind another, as in said patent.

45 In order to increase the range of usefulness of the machine, I also make provision for resetting or rearranging the blades as required for fan-fold work, so the machine may accommodate either the nest of folds, 50 as in Figs. 1 and 2, or the fan-fold 23, as in Fig. 3. For this purpose it is necessary to take off the upper blades 19 in each pair and turn them end over end and set them upon steps or mounts 15^b, which are provided upon the opposite side of the carbon carriage 14. These steps are higher than 55 the corresponding steps 15 in the first-described set, so that the blades 19 mounted thereon will lie at substantially the same 60 levels, respectively, as before. These additional steps are provided with holes or sockets for the blade dowels 20. The carbons 12 need to be attached in a slightly different manner to the blades 19 arranged 65 upon this side of the machine. They must

be inserted up-side down in the blades and with the sheets extending backwardly therefrom, and then the sheet 12 must be folded forwardly under the blade 19, as at Fig. 5. The blade 19 is provided with a clip 25 to 70 hold the carbon 12, as in Patent No. 1,177,546, dated March 28, 1916. The clip 25 is pivoted on a pin 25^a having a head to provide a finger-piece.

The inner set of steps 15^a may be made 75 detachable to permit transposition thereof, as suggested in Figs. 2 and 3. For this purpose, the latter-named steps are attached to the carbon carriage 14 by means of screws 26, entering holes 27 in the carriage. When 80 the machine operates on webs folded and tucked one within another, these steps 15^a are placed adjacent to the outer steps 15 on a suitable seat which may be at the same level as the seat for the similar set of steps 85 15, so that corresponding steps come at the same level in the two series of steps, in the manner represented in Fig. 2. But, if the machine is to be used for fan-fold work, then the detachable steps 15^a can be readily 90 transferred to a suitable seat on the opposite side of the carbon carriage, as indicated in Fig. 3, where they are designated by the reference character 15^b. It will be seen that the seat at the left in Figs. 2 and 3 is higher 95 than that at the right, so that the upper blades, although resting directly on the steps 15^a at the left, as shown in Fig. 3, will be at the same heights as when superimposed on the lower blades, as shown in Fig. 100. 2. The height of the seat at the left is greater than that at the right by the thickness of a lower blade 13 together with its clip 18. The heights of the supports and the thickness of the spacers 19^a are such as 105 to provide proper vertical spacing of the superimposed holders or blades 13 and 19, whether the upper blades 19 are supported at the right of the machine, as in Figs. 1, 2 and 4, or at the left, as in Fig. 3. Or, if desired, 110 the machine may be provided with the three sets of steps or mounts 15, 15^a and 15^b, as illustrated in Figs. 1 and 2. In any event, the machine can be employed for work either on webs composed of nests of 115 folds or on fan-folded webs, at option. The operation is the same in either case, save the positioning of the superposed sets of carbon-carrying blades, which are arranged as required for the respective folds. It is understood 120 that the webs with the interleaved carbons are guided together into the machine and fed around the revoluble platen 28, upon which they are advanced by the usual feed rolls to the printing line. The carbon carriage 14 meanwhile is drawn along the rails 29, as the typing is being 125 done. When this has been accomplished, the platen is separated from the feed rolls, as described in the said patents, and the 130

webs and carbons being released, the carbon carriage and holders are moved longitudinally of the folded plies to shift the carbons back to new positions along the webs.

Variations may be resorted to within the scope of the invention, and portions of the improvements may be used without others.

Having thus described my invention, I

10 claim:

1. In a typewriting machine, the combination with means for feeding a web formed with a plurality of plies whose folds are all along one side and having carbon-sheets interleaved between said plies, of a series of supports extending from front to rear of the machine, on one side thereof, said supports being of different heights, a plurality of superimposed carbon-sheet-holders on

15 each of said supports, and spacers between the superimposed holders, the heights of the supports and the thickness of each of the spacers being such as to provide proper vertical spacing of said holders.

25 2. In a typewriting machine, the combination with means for feeding a web formed of folded plies tucked one into another at one side and having carbon-sheets interleaved between said plies, of two series of

30 steps side by side at one side of the machine, lower blades for carbon-sheets resting on the steps of both series, means for retaining the lower blades on the outer steps, upper blades for carbon-sheets separated from the

35 steps of the inner series by the lower blades, and means for retaining said upper blades on the inner steps, said last-mentioned retaining means serving also as an additional retaining means for said lower blades.

40 3. The combination with means for feeding a multiple-ply work-web with interleaved carbon-sheets, of a pair of superimposed carbon-sheet-holders, means to secure said holders in position, comprising pins

45 projecting from the ends of said holders, and a support provided with sockets to receive said pins, the lower holder overlying the sockets for the pins of the upper holder, and being provided with openings register-

50 ing with the sockets for the pins of the upper holder.

4. In a typewriting machine, in combination, pairs of carbon-sheet holders, each pair comprising an upper holder and a lower holder, and a carbon-carriage comprising a stepped support adapted to support said

55 lower holders, fixed at one side of said carriage, a detachable support having steps corresponding to those of said fixed sup-

60 port, adapted to support said upper holders, a seat for said detachable support adjacent said fixed support, to position the former with its steps at the same heights as those of the latter, so that a lower holder and a

65 superimposed upper holder may be sup-

ported on a step of the fixed support and a step of the detachable support, and a seat for said detachable support on the opposite side of said carriage, the height of the last-mentioned seat being greater by the thickness of the lower holder than that of the first-mentioned seat.

5. In a typewriting machine, in combination, pairs of upper and lower carbon-sheet holders, the upper holder of each pair being 75 spaced from the lower, and a carriage for said holders comprising means whereby the pairs of holders while superimposed may be supported in stepped relation on one side of the carriage, and whereby the upper holders may be supported in reversed positions 80 at the other side of the carriage at the same heights as before, the upper holders in their reversed positions therefore assuming the same vertical spaced relation with reference 85 to the lower holders as when supported thereon.

6. In a typewriting machine, in combination, pairs of upper and lower carbon-sheet holders, the upper holder of each pair being 90 provided with means to space it from the lower holder when superimposed thereon, and means whereby the pairs of superimposed holders may be supported in stepped relation at one side of the machine, or the 95 lower holders may be supported in the same positions, and the upper holders, when reversed, may be supported on the opposite side of the machine at the same heights as before.

7. In a typewriting machine, in combination, pairs of superimposed carbon-sheet holders, the upper holder of each pair being spaced from the lower, and a carbon-carriage comprising a stepped support fixed at 105 one side thereof, adapted to receive a lower holder on each of its steps, a detachable support having steps corresponding to those of said fixed support, adapted to receive an upper holder on each of its steps, a seat for 110 said detachable support adjacent said fixed support to support the detachable support with its steps at the same heights as those of the fixed support, to enable the pairs of holders to be supported on the fixed sup-

115 port and the detachable support, and a seat for said detachable support at the opposite side of said carriage, the height of the last-mentioned seat being such that when the detachable support is positioned thereon 120 and the upper holders are reversed and placed on the steps of said detachable support, the upper holders will be supported at the same heights as before.

8. In a typewriting machine, the combination with means for leading a web longitudinally folded to form a nest of folds, interleaved with carbon sheets and closed all along one side thereof, of a carbon carrier, a support on the latter remote from the 130

- closed side of said nest, and sheet holders anchored one to another projecting from said support into the open folds.
9. In a typewriting machine, the combination with means for leading a longitudinally folded web having a plurality of plies held together all along one edge and carbon sheets interleaved between said plies, of a carbon carrier, a support on the latter remote from said folded edge, a sheet holder entering one of the folds of said web from said support, and a superimposed sheet holder anchored to said first-named holder in position to enter another fold of the web 15 on the same side. 70
10. In a typewriting machine, the combination with means for leading a web composed of a nest of folds tucked one within another with carbon sheets intermediate the several folds, of a carbon carrier, steps rising from said carrier at one side thereof, and a plurality of sheet holders projecting into separate folds from any one of said steps on the same side. 75
11. In a typewriting machine, the combination with means for leading a web having a plurality of plies all closed at one side and carbon sheets interleaved between said plies, of a carbon carrier, a support affording double bearing surfaces on said carrier laterally thereof, and carbon sheet holders projecting between the plies in the same direction from both of said surfaces. 80
12. In a typewriting machine, the combination with means for leading a web folded to form a plurality of plies whose folds are all along one side and containing carbon sheets interleaved between said plies, of a carrier for said sheets, a double line of supports mounted upon said carrier at the side thereof remote from said folds, and carbon sheet holders alternately anchored to outer and inner bearing faces of said supports and thence projecting between separate plies of said web. 85
13. In a typewriting machine, the combination with means for leading a web longitudinally folded to form a nest of folds all at one side, with carbon sheets interleaved between the several folds, of a carbon carrier, stepped supports mounted in a double series upon the side of said carrier remote from said folds, and superposed carbon sheet holders projecting into the latter all in the same direction from the various steps of said supports. 90
14. In a typewriting machine, the combination with means for leading a web formed with a plurality of plies whose folds are all along one side and interleaved with carbon sheets, of a carbon carrier, a support presenting double bearing surfaces on said carrier at the side thereof remote from said folds, a carbon sheet holder projecting into one of the folds from the outer bearing sur- 95
- face, a second holder superimposed upon said first named holder in position to enter another fold, and means for anchoring said second holder to both the inner bearing surface and the first holder. 100
15. In a typewriting machine, the combination with means for leading a longitudinally folded web with interleaved carbon sheets, of a carbon carrier, supports on both sides of the latter, an auxiliary support adjacent to one of said supports, and carbon sheet holders arranged to project into separate folds of said web from any two of the three supports, whereby the machine is adapted for work either on a web having 105 folds all along one side or upon a fan-folded web, at option. 110
16. The combination with means for feeding a multiple-ply work web, of pairs of blades for carrying carbons between the plies of the web, and an anchorage at one side of the web, a blade of each pair anchored at one end thereon and lying at the other end between the plies, and the other blade of the pair anchored on the first blade whereby removal of the first blade will effect removal of the other. 115
17. The combination with means for feeding a multiple-ply work-web, of pairs of carbon-carrying blades extending between the plies of said web, the blades of each pair being of different lengths, and means at one side of said web for supporting the blades of each of said pairs, whereby the free ends of said blades will be held in substantial alignment. 120
18. The combination with means for feeding a multiple-ply work-web, of groups of superposed holders for interleaved carbon sheets, each holder comprising a blade and a clip for holding the carbon sheet thereto, a support for the holders of each group, means for retaining each holder of a group on its support, and means whereby the retaining means for each holder may lock in 125 closed position the clip on the blade of the holder directly therebeneath. 130
19. The combination with means for feeding a multiple-ply work-web, of two carbon sheet-holders projecting into said web, each of said holders comprising a blade and a clip, supports for said holders, means to retain said holders on their supports, and means whereby the retaining means of one of said holders, when placed in coöperative relation with its support, will lock the clip on the other holder in gripping relation with its blade. 135
20. The combination with means for feeding a multiple-ply work-web, of a pair of superposed carbon sheet-holders, each comprising a blade, a clip pivoted thereon and a finger-piece at one end thereof, means to secure said holders in position, comprising pins projecting from the ends of said hold- 140

ers and a support provided with sockets to receive said pins, said sockets being so placed as to permit the upper holder to be displaced sufficiently on the lower, to avoid interference with the finger-piece on the latter, and means whereby the clip of the lower holder will be locked in gripping position when the upper holder is placed thereon.

21. In a typewriting machine, the combination with means for feeding a multiple-ply web having carbon-sheets interleaved between its plies, of a plurality of carbon-carrying blades arranged one overlying another in spaced superimposed relation and extending between said plies from the same side of the machine, and separate means for supporting each of said blades on the machine at one side thereof.

22. In a typewriting machine, the combination with means for feeding a multiple-ply web having carbon-sheets interleaved between its plies, of a plurality of carbon-carrying blades arranged one overlying another in spaced superimposed relation and extending between said plies from the same side of the machine, and separate means for supporting each of said blades on the machine at one side thereof, said supporting means for each of said blades being displaced laterally of the machine relatively to the supporting means for each of the other blades.
